SHAFT CORE DRILL

John Branner Newsom, Nevada City, Calif., assignor to Idaho Maryland Mines Corporation, San Francisco, Calif., a corporation of Nevada

Application November 23, 1936, Serial No. 112,266

11 Claims. (Cl. 255—4)

This application is a continuation in part of my application Serial No. 15,226 filed April 8, 1935, now Patent 2,065,725 of Dec. 29, 1936, for a Method of Core Drilling, and relates to core drills 5 for sinking mine shafts.

It has been the practice for many years to sink large size shafts such as mining shafts by means of explosives, and it is well known that the walls of a shaft sunk in this manner are rough 10 and irregular and consequently have to be timbered. In a mine of any size a crew has to be maintained for the sole purpose of replacing the shaft and tunnel timbers. Small diameter core drills have been used for many years, and are 15 familiar to most mining engineers. However, these drills have been used mainly for sampling and for providing passages for liquid. As far as I am aware, a core drill has never been designed and successfully employed prior to the development work on which this application is based, for 20 drilling large diameter shafts (five feet or larger) and to the depth required for mining operations.

One of the objects of this invention is the provision of a method of sinking a large diameter shaft in which a core drill is employed.

Another object of the invention is the provision of a mechanism for sinking a large diameter shaft comprising a cylindrical pilot house; a drive shaft depending from the pilot house and secured at 30 its lower end to a core drill; and means within the pilot house for rotating said shaft and controlling its vertical movement.

Another object of the invention is the provision of a core drill provided with a relatively 35 movable pilot house which may be occupied by an operator during the actual drilling operations.

Still another object of the invention is the provision of a combined core barrel and core pulley for removing cores from mine shafts.

The invention possesses other advantageous 40 features, some of which with the foregoing will be set forth at length in the following description where that form of the invention which has been selected for illustration in the drawings accompanying and forming a part of the present specification is outlined in full. In said drawings, one form of the invention is shown, but it is to be understood that it is not limited to such form, 45 since the invention as set forth in the claims may be embodied in a plurality of forms.

Referring to the drawings:

Figure 1 is a longitudinal cross section of a shaft drill embodying the objects of my invention.

Figure 2 is a longitudinal cross section of a

shaft drill taken at right angles to the drill shown in Figure 1.

Figure 3 is a plan view of the drill shown in Figure 1.

Figure 4 is a section taken on the line 4—4 of 5 Figure 2.

Figure 5 is a plan view of the spider shown intermediate the pilot house and core drill in Figure 1.

Figure 6 is a cross section taken on the line 10 6—6 of Figure 1.

Figure 7 is a vertical section taken through the combined core barrel and core puller shown in Figure 1 but with the core puller locked in engagement with the core.

Figure 8 is an enlarged detail section taken on the line 8—8 of Figure 6.

My invention contemplates the use of a cylindrical pilot house 1 within which is suspended a drive shaft 2, to which is secured at its lower 20 end a core drill 3. The pilot house and the core drill are preferably made from $\frac{1}{2}$ " plate, and the pilot house is reinforced by means of spaced channel bars 4, 5, 6 and 7, bent to conform to its shape and welded or otherwise secured thereto.

Supported by the lowermost channel bar 7 are 25 a pair of spaced I-beams 8 and 9 which in turn support the bearing members 11 and 12. The channel bar 6 supports a wood flooring 13 and also a pair of spaced channels 14 and 15, which in turn support a plate 16. Depending from and secured to the plate 16 is a bearing 17 in alignment with the bearing 11 and within which the shaft 2 is adapted to rotate. Keyed to the shaft 2 between the bearings 11 and 11 is a bull or

gear wheel 18 adapted to be driven by a pinion 19 carried by the horizontal shaft 21, which in turn is supported by spaced bearings 12 and 22. Secured to the intermediate portion of the shaft 21 is a gear 23 adapted to be driven by the belt 30 40

24 which passes over the pulley 25 of the motor 26. As shown in Figures 1 and 2, the motor 26 is supported by the channel bars 14 and 15. Extending upwardly from the plate 16 is a rectangular frame made up of channel bars 26' which 45 may be secured to the plate 16 and to the roof or ceiling 27 of the pilot house in any suitable manner, such as for example by angle bars 28 and plates 29. Secured to the lower side of the roof 27 are a pair of spaced depending brackets 50 55 31 which serve as bearings for the shaft 32 and to the outer ends of which are attached pulleys 33. Slidably disposed within the rectangular frame formed by the channel bars 26' is a block 34 adapted to engage the lower face of a collar

- 35 bolted or otherwise secured to the shaft 2. The block 34 and in turn the shaft 2 are adapted to be lowered and raised by a winch 36 operatively connected to the block 34 by ropes or cables 37.
- 5 Disposed at spaced points within the channel bars 4 and 5 are a plurality of wall jacks consisting of nuts 38 held in position by clips 39 and screws 41 passing through the nuts and adapted to be driven into the walls of the shaft 42.
- 10 The function of the screws 41 is to center and level the cylindrical pilot house 1 within the shaft and to simultaneously anchor it within the shaft in its centered position. As an aid in leveling the pilot house, spirit levels may be 15 conveniently located on its framework.
- 15 The core drill 3 comprises a cylindrical core barrel 104 surrounded at its upper end with a plate 105 and carrying at its lower end a drill-shoe 106. The shoe 106 is formed with a recess 20 107 for receiving the lower end of the barrel 104 and it is to be noted that the only portions of the core drill engaging the walls of the shaft are the plate 105 and the outer surface of the shoe 106. By using this type of construction the 25 frictional resistance between the core drill and the shaft is materially reduced, thereby permitting the motor 26 to be much smaller than would otherwise be necessary. The shoe 106 is provided with slots 108 for accommodating shot 30 in the usual manner. Secured within the upper inner end of the barrel 104 is a band 109 of angle iron, to the under face of which are riveted two diametrically opposed sets of plates 111. Riveted to the lower faces of these plates is a 35 pair of angle irons 112 symmetrically disposed on either side of a diameter of the core barrel. Diametrically opposed to the plates 111 and riveted to the upper face of the band 109 are two diametrically opposed sets of plates 113. Riveted 40 to the plates 113 and to plates 114 carried on the angle irons 112 are spaced angle irons 115. Accommodated within the central square defined by the angle irons 112 and 115 is a block 116 through 45 which the lower end of the shaft 2 is threaded and which is secured in place by a bolt 117 passing through the shaft 2, block 116 and angle irons 115. Angle irons 118 riveted to the band 109 serve as rests for supporting the pilot house 1 or a spider to be later described.
- 50 Telescopically disposed within the core barrel 104 is a cylindrical core puller 121 formed with longitudinal slots 122 for permitting its lower end to be radially contracted or expanded. The lower peripheral surface of the core puller 121 55 is provided with dogs or serrations 123 for gripping the core 124 and with an inclined or beveled surface 125 adapted to engage a complementary inclined surface 126 formed on the shoe 106. Extending across and secured to the angle irons 112 60 are pins 127 arranged to carry latches 128. The depending ends of the latches 128 are adapted to engage a band 129 riveted or welded to the upper end of the core barrel 121. Removable bolts 131 associated with angle irons 112 serve to lock 65 the latches 128 in engagement with the band 129. Secured to and in spaced relation about the band 129 are a number of upwardly extending arms 132, the upper ends of which are apertured in order to accommodate cables for moving 70 the core puller 121 longitudinally with respect to the core barrel 104.

In view of the above construction it will be seen that with the core puller 121 held in its suspended position by the latches 128 as shown in Figure 1, the serrations 123 of the core puller are free

and clear of the core 124. By disengaging the latches 128 from the band 129 and raising the core barrel 104, the relative movement between the complementary beveled or inclined surfaces 125 and 126 so produced, wedges the serrations 123 in engagement with the core 124. To release the core, the core puller 121 is moved upwardly relative to the core barrel 104.

In my prior application above referred to, one method of breaking a core off at its base was described. According to that method, the core was broken off by the use of a wedge inserted in the kerf formed as a result of the drilling operation. The same result may be obtained by setting off a charge of dynamite at the bottom of the kerf. For this purpose, as shown in Figures 6 and 8, a pipe 133 extending through the angle iron 109, between the core barrel and core puller, and through the drill shoe 106, is provided so that a stick of dynamite 134 may be lowered to the bottom of the kerf 135 and set off either by means of a fuse or a remote control electrical circuit. The pipe 133 serves to key the core barrel to the core puller, although other means may be provided for the purpose of preventing relative rotation between these two members. In either case, that is, whether a wedge or dynamite is used, it is essential that the length of the core 124 be not less than its diameter, for the fracture produced by either means will take the shortest path. If the length of the core is greater than its diameter, the shortest possible line of fracture starting from any point at the base of the kerf is in a plane substantially at right angles to the axis of the core. If on the other hand the diameter of the core is greater than its length, any other line or plane of fracture is shorter than a line or plane taken along a diameter of the core.

Intermediate the pilot house 1 and the core drill 3 is a spider generally designated as 48, comprising a frame 51 adapted to carry a plurality of spaced screws 52. The center of the frame 51 serves as a bearing for the shaft 2, and therefore it will be seen that the spider 48 may be used to prevent the shaft 2 from whipping when the core drill is in its extended position. Although not shown, the spider 48 is provided with means for suspending it from the pilot house and holding it in any predetermined position while the screws 52 are being adjusted.

As best shown in Figure 3 the plate 27 which forms the ceiling of the pilot house 1 is provided with trap doors 55 and 56 through which an operator may pass in order to gain entrance to the 55 pilot house. The upper periphery of the shell of the pilot house 1 extends above the ceiling 27 and is bent inwardly as at 57 (Figures 1 and 2) so that the pilot house may be pulled upwardly within the shaft. In effect this upper periphery of the 60 pilot house shell forms a guide member for the pilot house during its upward movement through the shaft. To the upper end of the shaft 2 is bolted a ring 58 to which a cable may be secured for the purpose of raising and lowering the entire mechanism, and also for the purpose of suspending the shaft drill in any predetermined position. If desired, the ring 58 may be a swiveled ring so that the cable can twist without producing a torque on the drill. Ordinarily the screws 41 serve to anchor the pilot house in position, but as a safeguard it is advisable to keep the cable secured to the ring 58 taut so that if by any chance the screws 41 give way, there will be no danger of dropping the entire mechanism.

The operation of the drill as above described is as follows: If the shaft has been partially bored, the muck is removed from the bottom of the shaft and the bottom of the shaft cleaned up by means of a skip operating in the usual manner, but without the use of guides secured to the walls of the shaft. Guides cannot be used for the reason that the entire drill must be periodically raised to the top of the shaft in order to remove the core. The shaft drill is lowered to the bottom of the shaft by means of the cable secured to the ring 58, so that the core drill 3 rests on the floor of the shaft. The pilot house is then centered within the shaft and anchored therein by means of the screws 41. The operator who is standing on the floor 13 of the pilot house starts the electric motor 26 which is supplied with electric current by means of suitable cables, passing upwardly through the ceiling of the pilot house to the top of the shaft. Preferably the motor 26 should be of the variable speed type. Obviously the rotation of the motor operates to rotate the shaft 2 and consequently the core drill 3. As is the usual practice, steel shots are periodically introduced to the bottom of the drill shoe 106 and this is preferably accomplished by introducing the shot between the walls of the shaft 42 and the outer base of the core barrel 104. At this time the spider 49 may be allowed to rest on top of the core drill 3. The core drill is then gradually lowered as the drilling progresses, by means of the winch 36. In this connection it should be particularly noted that since the core drill is about ten feet long the operator is always within 20 or 25 feet of the cutting edge of the core drill. This is of considerable importance for the rate of lowering the core drill depends entirely upon the nature of the rock through which the shaft is being sunk, and this in turn can only be determined by sound, by the heat generated in drilling, and by the manner in which the drill appears to be operating. The rate at which drilling is allowed to progress is largely a matter of experience, but the judgment of the operator is materially aided by being close to the point of operation rather than at a remote distance as is the case in most drilling operations. After the core drill 3 has progressed several feet it may then be advantageous to adjust the spider 49 intermediate the core drill and the pilot house for the purpose of preventing any whipping or lashing of the shaft 2. This may be done by the operator by lowering himself through a trap door in the floor 13 and lowering the spider 49 to the desired point by means of suitable cables as above described and then adjusting the screws 52. The drilling operation produces cuttings in the form of heavy sand which can be collected as drilling progresses by means of a bucket resting on top of the core, all as set forth in my application Serial No. 15,226.

When the core drill 3 has completed its full stroke of ten feet or so, the core is broken away at its base as previously described. In breaking the core off, the core drill is raised a foot or so in order to allow room for the stick of dynamite introduced through the pipe 133. After the core is broken off, the core barrel and core puller are lowered to the bottom of the kerf, the core puller is released from the latches 128, and the entire mechanism is raised to the surface by means of the hoisting cable secured to the ring 58. As above explained, the upward movement of the core barrel relative to the core puller causes the serrations 123 to grip the core and

thereby lift the core to the surface with the entire mechanism. At the surface the drill together with the core is moved to one side by means of a crane and while the core is being released from the core puller the shaft can be cleaned out in preparation for a further drilling operation. 5

During the past year a shaft drill as above described has been used under my direction for drilling a five foot diameter shaft at the Idaho Maryland mine in Grass Valley, California, and although numerous changes in design had to be made as the work progressed, a shaft over 1100 feet in depth was drilled at a cost considerably under the costs usually incurred in similar drilling operations. 15

If the motor should burn out, noxious gases would be produced which might suffocate the operator. Furthermore, considerable heat is developed during the drilling operation. For these reasons it has been found desirable to provide the pilot house with a valved air line extending from the top of the shaft so that a controlled supply of air may always be available. 20

"Cylindrical" as herein used in reference to the pilot house 1 is not to be construed as limited to 25 a circular cylinder but rather in its broad geometric sense. As a matter of fact, the pilot house may consist of merely a suitable framework covered at the top to protect the operator and containing the working mechanism above 30 described.

I claim:

1. A shaft sinking mechanism comprising: a cylindrical pilot house; a core drill disposed below and co-axially with said pilot house, the length of 35 said core drill being not less than its diameter; a drive shaft movably suspended from the pilot house and secured at its lower end to the core drill; and means within the pilot house for rotating said shaft and controlling the relative 40 longitudinal movement between the shaft and the pilot house.

2. A shaft sinking mechanism comprising: a cylindrical pilot house; means associated with 45 said pilot house for detachably securing it in any pre-determined position within a shaft; a core drill disposed below and co-axially with said pilot house, the length of said core drill being not less than its diameter; a drive shaft movably suspended from the pilot house and secured 50 at its lower end to the core drill; and means within the pilot house for rotating said shaft and controlling the relative longitudinal movement between the shaft and the pilot house.

3. A shaft sinking mechanism comprising: a cylindrical pilot house; a core drill disposed below and co-axially with said pilot house, the length of 55 said core drill being not less than its diameter; a drive shaft movably suspended from the pilot house and secured at its lower end to the core drill; a spider intermediate the pilot house and core drill for supporting the drive shaft against lateral movement; and means within the pilot house for rotating said shaft and controlling the relative longitudinal movement between the shaft and the pilot house. 60

4. A shaft sinking mechanism comprising: a closed cylindrical pilot house; a drive shaft depending from the pilot house and secured at its lower end to a core drill, the length of said core 70 drill being not less than its diameter; and means within the pilot house for rotating said shaft and controlling its vertical movement.

5. A shaft sinking mechanism comprising: a cylindrical pilot house having a floor and ceiling; 75

- doors in said floor and ceiling for permitting an operator to pass therethrough; a drive shaft depending from the pilot house and secured at its lower end to a core drill, the length of said core drill being not less than its diameter; and means within the pilot house for rotating said shaft and controlling the relative longitudinal movement between the shaft and the pilot house.
6. A shaft sinking mechanism comprising: a cylindrical pilot house; a plurality of spaced individually operated screws extending outwardly through said pilot house for centering and securing the pilot house in any predetermined position within a shaft; a drive shaft extending through the pilot house and secured at its lower end to a core drill, the length of said core drill being not less than its diameter; a gear wheel seated within the pilot house and keyed to the drive shaft so as to permit relative longitudinal movement between the gear wheel and the drive shaft; means for rotating the gear wheel and means within the pilot house for lowering and raising the drive shaft.
7. A shaft sinking mechanism comprising: a cylindrical pilot house; a drive shaft extending through said pilot house and secured at its lower end to a core barrel; a cylindrical core puller telescopically disposed within said core barrel; means for radially expanding and contracting the lower periphery of said core puller; and means within said pilot house for rotating the drive shaft and controlling its vertical movement.
8. A shaft sinking mechanism comprising: a cylindrical pilot house; a drive shaft extending through the lower end of said pilot house and secured at its lower end to a core barrel; a cylindrical core puller telescopically disposed within said core barrel; inclined complementary surfaces formed on the lower ends of said core barrel and core puller for contracting the lower

periphery of the core puller on relative longitudinal movement between the core barrel and core puller; and means within said pilot house for rotating the drive shaft and controlling its vertical movement.

9. A shaft sinking mechanism comprising: a cylindrical pilot house; a drive shaft extending through the lower end of said pilot house and secured at its lower end to a core barrel; a drill shoe secured to the foot of said core barrel; a cylindrical core puller telescopically disposed within said core barrel; means for radially contracting the lower periphery of said core puller; means within said pilot house for rotating said drive shaft; and a longitudinal passageway extending through said drill shoe for admitting a charge of dynamite to a point below said shoe.

10. A shaft sinking mechanism comprising: a cylindrical pilot house; a drive shaft extending through the lower end of said pilot house and secured at its lower end to a core barrel; a cylindrical core puller telescopically disposed within said core barrel; latch means for suspending said core puller within the core barrel; means for radially contracting the lower periphery of said core puller; and means within said pilot house for rotating the drive shaft and controlling its vertical movement.

11. A shaft sinking mechanism comprising: a closed cylindrical pilot house; a drive shaft extending through the lower end of said pilot house and secured at its lower end to a core barrel; a drill shoe secured to the foot of said core barrel, the outer diameter of said shoe being greater than the outer diameter of said barrel; a band secured to the outer periphery of the upper end of said barrel, the outer diameter of said band being substantially equal to the outer diameter of said drill shoe; and means within the pilot house for rotating said shaft.

JOHN BRANNER NEWSOM.
